UNITED STATES PATENT OFFICE

LOUIS LUDWIG, OF BROOKLYN, NEW YORK

DESIGN FOR A TOBACCO-ASH RECEIVER

Application filed June 24, 1929. Serial No. 31,824. Term of patent 3½ years.

To all whom it may concern:

Be it known that I, LOUIS LUDWIG, a citizen of the United States, residing in Brooklyn, county of Kings, State of New York, have invented a new, original, and ornamental Design for a Tobacco-Ash Receiver, of which the following is a specification, reference being had to the accompanying drawing, forming part thereof.

In the drawing Fig. 1 is a front elevation, Fig. 2 a side elevation, and Fig. 3 a top view of a tobacco-ash receiver, showing my new design.

I claim:

The ornamental design for a tobacco-ash receiver, as shown.

LOUIS LUDWIG.
